Primary Examiner — Rashida C. Walshon(74) Attorney, Agent, or Firm — Quarles & Brady LLP(57) CLAIM

The ornamental design for a sandal, as shown and described.

DESCRIPTION

FIG. 1 is a top, right, front perspective view of the sandal showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The dashed lines illustrate portions of the sandal that form no part of the claimed design.

1 Claim, 7 Drawing Sheets(56)
